UNITED STATES PATENT OFFICE.

WICK HATHAWAY, OF MADISON, OHIO.

DESIGN FOR A BUTTER-KNIFE.

SPECIFICATION forming part of Design No. 35,554, dated January 7, 1902.

Application filed December 13, 1901. Serial No. 85,854. Term of patent 14 years.

To all whom it may concern:

Be it known that I, WICK HATHAWAY, a citizen of the United States, residing at and whose post-office address is Madison, in the county of Lake and State of Ohio, have produced a new and original Design for a Butter-Knife, of which the following is a specification, the construction being illustrated in the accompanying drawings, in which—

10 Figure 1 is a side elevation of a butter-knife constructed in accordance with my invention, and Fig. 2 is a sectional view on the line xx of Fig. 1.

15 1 designates a handle cylindrical in form, on one end of which is a disk 2. Near the disk and arranged on either side of the handle are a plurality of notches 3. A blade 4 projects from the other end of the handle, the upper

edge of which is curved in graceful lines to the extreme end thereof, as at 5. The blade 20 4 is reduced in width at the juncture of the same with the handle, as shown at 6, and a scalloped rib or ridge 7 is arranged in the upper edge of the knife, the lower edge of which consists of a plurality of curvatures. 25

What I claim, and desire to secure by Letters Patent, is—

The design for a butter-knife, substantially as herein shown and described.

In testimony whereof I affix my signature 30 in presence of two witnesses.

WICK HATHAWAY.

Witnesses:

ERNEST HATHAWAY,
